UNITED STATES PATENT OFFICE.

STEPHEN D. MURRAY, OF DALLAS, TEXAS.

COTTON-GIN.

1,089,255.

Specification of Letters Patent. Patented Mar. 3, 1914.

Application filed September 13, 1907. Serial No. 392,652.

To all whom it may concern:

Be it known that I, STEPHEN D. MURRAY, a citizen of the United States, residing at Dallas, in the county of Dallas and State of Texas, have invented new and useful Improvements in Cotton-Gins, of which the following is a specification.

This invention relates to cotton gins embodying a brush cylinder, and the objects of the same are to provide a strong and durable cotton gin frame comprising a simple organization wherein the number of parts is reduced to a minimum, and a gin with a longitudinal tubular member having a brush cylinder coöperating therewith and which serves as a conduit for the passage of the lint cotton from the gin and also as a connecting means for the legs of the gin frame and as an end outlet for the gin, and leaving the rear of the latter unobstructed and freely accessible.

The improved construction of gin frame including the longitudinal tubular member may be embodied in a single gin organization, and consisting of three members, two end or leg members and a single longitudinal member or tube, or a double gin frame may be made of only four members, three leg members and one longitudinal member.

The number of gins included in a battery of gins, and involving the improved frame structure may be modified at will, and the intermediate leg members are varied in their construction with respect to the end leg members, as will be more fully hereinafter specified. The salient feature of the present invention is, however, a tubular member longitudinally disposed in the body of the gin and lying along the ginning mechanism, and particularly in combination with a brush cylinder in contradistinction to a gin structure, wherein a brush cylinder is not used. Aside from the function of the tubular member as a lint flue or conduit and independently of said function, the tubular member greatly increases the rigidity and stiffness of the gin frame, the tubular member or tube preferably forming a part of the gin frame structure, for rigidly securing the legs in their relative positions to each other, and aside from this important function, the tubular member or tube passing through the gin or gins and through the legs thereof has many advantages in structural condensation,

requiring very much less room and forming a more direct passage for the lint from the

gin brushes, with less superficial area in the lint flue, dispensing with the short lint flue connections, and various angles and turns found in present gin flue constructions, and which cause frictional resistance to the air currents. Frictional resistance to the air currents is greatly lessened by placing the tubular member or lint flue within the gin or gins and adjacent to the brushes, and consequently the efficiency of cotton gin structures is thus also materially increased. The most essential feature of the invention, therefore, is the tubular member within the body of the gin in contradistinction to the tubular flues disposed at the back portions of gins and usually having communicating flues extending through the rear of the gin structures at an angle to the ginning mechanism. The tubular member of the present invention is of uniform diameter throughout its length and in this respect essentially differs from lint flues or tubular devices which gradually increase in diameter from a minimum to a maximum diameter to avoid deposits or clogging of the lint cotton in the flue in accordance with the gin organizations as heretofore constructed. The gradual or constantly increasing dimensions of the lint flues as heretofore constructed toward the delivery or outlet ends was necessary to reduce the resistance or to maintain the latter as small as possible. In gins embodying brushes and having lint flues as heretofore constructed, the revolution of the brushes effected an indrawing of a volume of air and an expulsion of the air rearwardly into the flue in such manner that the velocity was comparatively low and the volume of the air very large, and for this reason the lint flue was required to be large toward the outlet end or gradually increasing from the initial end thereof in connection with the first gin toward the outlet extremity thereof beyond the last gin. By the use of the tubular member the cost of production of gins is lessened, and also the cost of the building in which such gins are installed.

The use of the tubular member with a brush cylinder is not confined to any particular type of gin, and may be introduced and perform its desired functions in any gin having a brush cylinder.

In the drawings: Figure 1 is a front elevation of a battery of gins showing the improved structure applied thereto. Fig. 2 is

a transverse vertical section on the line 2—2, Fig. 1. Figs. 3, 4 and 5 are detail views of the leg devices or structures embodied in the gin.

5 Similar characters of reference are employed to indicate corresponding parts in the views.

Fig. 1 shows a battery of gins including four gins and consisting of two double or 10 twin gins, each of the said double gins being made up of a tube with three legs, and between the legs the ginning devices, such as the roll-box, saw cylinder, brush, etc. are disposed in each gin.

15 The numeral 1 designates a cast-metal leg for supporting the gin, which is applied at opposite ends of a gin, as shown by Fig. 1, the said leg being shown in reverse position by Figs. 3 and 4, and each has an opening 20 2 therein, surrounded by a flange 3. Each leg also has a contour and is provided with bearing means and projections to adapt it for assemblage with the remaining parts of the gin, the use of all bonding rods and se-

25 curing devices for gin legs being dispensed with, and in lieu thereof a particular tubular connecting means is employed and has a dual function, as will be more particularly hereinafter specified. The intermediate leg 30 shown by Fig. 5, and designated by the numeral 5, is practically composed of two of the legs shown by Figs. 3 and 4, and in use is arranged between contiguous ends of the double or twin gins, as shown by Fig. 1.

35 The two plates 6, of the leg 5, are made as one casting and joined or connected by a tubular coupling 7, which has an interior diameter greater than the exterior diameter of the essential element of the invention, 40 and which passes therethrough.

Each individual gin, to which in the present instance the features of the invention 45 have been shown applied, comprises a roll-box 8, provided with a breast-plate 9, and having end castings 10, to which the roll-

50 box plate is secured by riveting, or by any other suitable means. The upper and lower rib rails 11 and 12 respectively have the upper and lower extremities of the ribs or grates 13 secured thereto in the usual manner and are disposed in operative relation to the saws of the saw-cylinder 14. The gin structure also embodies a seed-hopper 15, having a latch 16 fixed thereto and adapted

55 to hold the lower portion of the roll-box up when lifted out of operative connection with the saw cylinder. A bracket 17 fixed to the lower portion of the roll-box catches upon the latch 16 when the said lower portion of 60 the roll-box is elevated. The end plates of the roll-box are also provided with pivotal boss means 18, which engage recesses or notches 19 in the upper portions of the gin legs, bolts 20 being inserted through the

65 upper portions of the gin legs above the

bosses to prevent the latter from accidentally becoming displaced or lifting out of the said recesses or notches 19.

At the upper rear portion of the roll-box 8, a curved plate 21 is secured and forms what is known as the "back hollow" of the roll-box. It will be noted that this plate 21 passes down and around the upper rib rail 11, and provides an armor plate or sheathing for the latter, the said rib rail 11 being securely held or reinforced against splitting by bolts 22 passed therethrough and the said plate 21. The gin organization also includes a gin brush 23, over which is a fixed top cover 24, and at the rear of the brush or brush cylinder is a removable cover 25 to permit ready access to the same. The all-controlling element of the invention, however, is a tubular member or tube 26 which serves both as a means for connecting the legs or end members of the gin and as a conduit for the lint cotton, and is provided with an upper opening 27.

The function of the tubular member in connecting the legs or end members of the gin is only incidental or secondary to the more important function of the said member as a conduit for the lint cotton. As hereinbefore specified, the said tubular member is of uniform diameter throughout its length 95 or throughout the battery of gins with which it is used and is of comparatively reduced diameter, and under these conditions will perform its function as a conduit for the lint cotton equally well with a battery 100 of two gins and a greater number of gins.

The lint cotton is conducted to the tubular member by means of a part 28 which, in the present instance, is in effect a plate having one end arranged adjacent to the mote 105 plate 29 or in correct position to receive the material from the brush, the opposite end of the plate projecting into the tubular member, serving not only as a nozzle or chute to conduct the material from the revolving 110 brush into the tubular conduit, but that portion thereof projecting into the tubular member also serves as a deflector to prevent the cotton lint that has a circulating motion in the conduit, from driving upwardly and 115 returning to the revolving brush.

As a means of connecting the legs or end members of the gin, the tubular member or tube 26 is highly efficient in that it strengthens the gin frame as an entirety and dispenses with the use of tie rods or other connecting means between the legs or end members of the gin frame and thus facilitates the assemblage of said legs.

The tubular member or tube 26 extends 125 continuously through the length of the double gin and through the coupling 7 of the middle legs consisting of the two plates 6, the opposite ends or extremities of the tubular member or tube 26 being continued 130

beyond the end legs 1 of the double gin, as shown by Fig. 1, and between the double gins the projecting ends of the tubular member are made continuous by applying a connection, as 7^a, in the form of a thin sheet of metal, which is merely telescoped over the protruding ends of the tubular members of the two double gins, or by preference this thin sheet of metal is merely wrapped around the projecting ends of the tubular member. This construction will be duplicated throughout the entire series of double gins included in a battery comprising any number of such double gins.

15 It will be observed that the brush cylinder 23 is arranged in close proximity to the inlet of the chute 28 of the tubular member or tube 26, and the lint cotton released from the saws is caused to pass through the said chute into the tubular member. The direction of movement of the brush cylinder drives the air laden with the lint downwardly into the tubular member 26 through the chute 28.

20 25 It will be observed that the upper edge of the mote plate 29 is disposed close to the brush cylinder 23, thus forming a materially reduced passage between the brush cylinder and the upper edge of the mote plate, the adjustment of the upper edge of the mote plate being along a line parallel with the periphery of the brush cylinder. The mote plate will be provided with suitable adjusting means as indicated in the drawings, and 30 35 by providing the adjusting means for the mote plate the upper edge of the latter may be fixed at a point to secure the maximum moting effect. The material feature in regard to the position of the upper edge of the mote plate relatively to the brush cylinder is to produce an air inlet opening which is so narrow as to permit the passage of only about one-third of the air between the upper edge of the mote plate and brush cylinder in contradistinction to the prior well known gin organizations and wherein the mote plate has its upper edge disposed at a considerable distance from the brush cylinder. By arranging the upper edge of 40 45 50 the mote plate in close proximity to the brush cylinder the air is confined in its passage between the upper edge of the mote plate and the cylinder to a thin stratum and is given an increased velocity in a downward direction, and the air between the upper edge of the mote plate is driven by the incoming currents through the constricted passage between the upper edge of the mote plate and brush cylinder and driven into the 55 60 65 tubular member or lint flue 26. The thin stratum of air which is drawn between the brush cylinder and upper edge of the mote plate by reason of the formation of the constricted passage therefor, as just explained, being less in quantity and of higher velocity

than in the ordinary and well known gin organizations permits of the tubular member or lint flue being of materially less diameter than was found necessary in the old style of gins using flues exteriorly thereof. 70 Furthermore, the tubular member or lint flue is disposed in close relation to the brush cylinders of the gins, and as a consequence the short connecting flues with various angles, turns and resulting eddies as found in the old style of gins are eliminated, thereby increasing the capacity of the flue embodied in the present invention as a conduit means for the air and lint from the brush cylinders. By extending the plate 80 28, which serves as a chute or deflector plate, into the entrance opening of the tubular member or lint flue, swirling of the air and lint in the flue is prevented from adversely affecting the air current which carries the 85 lint cotton into the flue or tube and materially assists in setting up a quick movement or travel of the currents of air laden with lint cotton longitudinally through the tubular member.

90 The lint cotton delivered into the tubular member is conveyed or moved through the latter to any suitable point for further treatment, and the ginning operation is greatly accelerated by the use of the tubular 95 member, and the combination therewith of the brush cylinder disposed adjacent thereto, as hereinbefore specified.

The terms "tube" and "tubular member" as applied to the part 26 in the foregoing description have been employed to conveniently illustrate one preferred embodiment of the essential feature of the invention, and such terms should not be construed or interpreted in accordance with the literal definition of the words "tube" and "tubular member," but, on the contrary, should be interpreted to include a hollow member or conduit means of any preferred form in cross-section applicable 100 105 for coöperation with the ginning mechanism and including the brush cylinder. A change in the cross-sectional contour of the tube, tubular member or conduit would not effect the practical result sought and obtained by the introduction of such device 110 within the gin organization, and it will therefore be properly inferred that the particular advantageous operation or function of the conduit is sought, as hereinbefore explained, rather than a specific cross-sectional contour of such conduit.

115 120 125 In my copending application relating to cotton gins, Serial Number 199,514, filed March 23, 1904, the tube, tubular member, or conduit is disclosed as the most essential feature in a gin organization without a brush cylinder or necessary restriction as to particular means for setting up an air current for driving the lint cotton into the 130

tube, tubular member or conduit. In this application particular stress is laid upon the use with the tube, tubular member or conduit of a brush cylinder as the distinguishing feature, the said brush cylinder creating a conveying current for the lint cotton with relation to the tube, tubular member or conduit. The invention as disclosed herein, therefore, is a modified continuation of that disclosed in my above mentioned copending application filed March 23, 1904.

From the foregoing disclosure it will be understood that the primary or most essential feature of the invention is the tubular member of uniform diameter throughout its length within the body of the gins and serving as a lint conduit means for a battery of gins varying in number and incidentally or as a secondary feature operating as a securing means for the ends of the frame of the gin; the disposition of the tubular member in close proximity to the ginning devices and particularly the brush cylinders of the gins and providing a contracted space between the upper edges of the mote plates and the brush cylinders to effect an indrawing of a thin stratum of air to decrease the quantity of air between the mote plates and brush cylinders at the nearest approach of said plates to the cylinders, and increase the velocity of the air at such points, so that the brush cylinders will cause a downward deflection of the air carrying the cotton at a high rate of speed into the tubular member over plates or chutes extended or projected into the inlets of the tubular member at an angle relatively to the wall of the tubular member to accelerate the movement of the air currents laden with cotton longitudinally through the tubular member.

Having thus described the invention, what is claimed is:

1. In a cotton gin, the combination with supporting legs, of a longitudinal hollow member uniting the legs and operating as a receptive means for the lint and having a lint-receiving opening, and ginning devices including a brush cylinder arranged to discharge into the lint-receiving opening of the member, the hollow member extending along the brush cylinder.

2. In a cotton gin, the combination of ginning mechanism including a brush cylinder, and a main hollow lint receiving member extending longitudinally through the body of the gin and forming the direct outlet for the lint cotton from the gin, a guiding means between the cylinder and conduit and tangentially arranged in relation to the latter, the brush cylinder being arranged above the hollow member and operating to produce an air current in the direction of and in the said member to drive the lint cotton into and through the latter.

3. In a cotton ginning apparatus, the combination with a plurality of gins, a main hollow lint receiving member disposed longitudinally in the gins and extending endwise through the latter and continuous with respect to all the gins, the hollow member having angularly disposed inlets communicating with the gins, and ginning mechanism including brush cylinders, each brush cylinder being disposed in proximity to an inlet portion of the hollow member, the one extremity of each inlet being tangentially arranged in relation to and closely associated with each brush cylinder, a thin stratum of air of high velocity being produced adjacent to each brush cylinder and operating to drive the lint cotton into the hollow member.

4. The combination with a plurality of gins having ginning mechanism therein including brush cylinders, of a longitudinal conduit extending through the bodies of the several gins and rigidly uniting the legs of the latter, and also serving as a receptive medium for the lint, the brush cylinders being disposed in co-operative relation to the conduit and operating to drive the lint cotton into the latter.

5. The combination with a plurality of gins having supporting legs, of a hollow member longitudinally extending through the gins and secured to and rigidly uniting the frames of the gins, and ginning mechanism in each gin including a brush cylinder disposed in co-operative relation with the portion of the hollow member passing therethrough and operating to drive the lint cotton into said member.

6. In a cotton gin, the combination with ginning mechanism including a brush cylinder, of a hollow member extending longitudinally through the gin and having an opening, the brush cylinder being disposed adjacent to the said opening, and a chute projecting in the said member through the opening therein and having a device co-operating with the upper portion thereof and its edges projected close to the brush cylinder to provide a narrow air passage in relation to said cylinder.

7. The combination of a plurality of gins arranged end to end and having intermediate legs consisting of double plates connected by a hollow coupling, ginning mechanism, and a hollow member extending longitudinally through the gins and the hollow couplings of the legs and operating to secure the gin frames in rigid relation and also as a lint receiving medium.

8. The combination of a plurality of gins arranged end to end and having intermediate legs consisting of double plates connected by a hollow coupling, ginning mechanism, and a hollow member extending longitudinally through the gins and through the

- hollow couplings of the legs and operating to secure the gin frames in rigid relation and also serving as a lint cotton receiving and conveying means for each gin and for 5 all of the gins as a whole, the hollow member being located beneath and adjacent to the ginning mechanism of each gin and having the currents of air produced therein by the operation of the ginning mechanism.
9. The combination with a cotton gin, of a tube contained within the gin body and having an opening therein and serving to receive and conduct the lint cotton out through the end of the gin, and ginning mechanism including a brush cylinder located adjacent to the opening in the said tube and operating to drive the lint cotton into the tube.
10. The combination with a plurality of 20 gins having ginning devices including brush cylinders, a tubular member passing through the extremities of the gins and having openings therein disposed in proximity to the brush cylinders, mote plates having their 25 moting edges arranged closely to the brush cylinders to form narrow air passages with relation to said cylinders, and deflecting plates extending from the mote plates into the openings in the hollow member.
11. The combination with a gin having 30 ginning devices, including a brush cylinder, and legs for supporting the ginning devices, a conduit having an opening and acting as a longitudinal portion of the gin frame to rigidly hold the legs of the gin in position, and a plate extending from a point adjacent to the brush cylinder downwardly and rearwardly into the opening in the conduit to form a chute projecting into the conduit.
12. The combination with a plurality of 40 gins, each gin having ginning devices including a brush cylinder, and legs in each gin for supporting the ginning devices, a hollow member in each gin acting as the longitudinal portion of the gin frame and rigidly securing the legs of the gin in position, the said hollow members of the different gins being extended through the gin 45 legs and connected at their adjacent terminals to form a common conduit into which the cotton is directed by the brush cylinders and conducted away from the gins.
13. In a gin, embodying suitable ginning 50 devices including a revoluble brush, a hollow member arranged adjacent to the periphery of the brush and having a lint-receiving opening therein through which the lint from the brush is discharged into the 55 hollow member, and an angularly disposed plate projecting into the hollow member in proximity to the opening therein for preventing escape of the lint from the tubular member to the brush, the upper portion of 60 the plate having a mote plate the moting edge of which is arranged near the brush to form a narrow air passage with relation to the latter and to produce a thin film of air of high force and velocity to carry the lint cotton into the hollow member. 70
14. In a gin embodying suitable ginning devices embodying a revoluble brush, and supporting legs, a hollow member extending between the legs and in proximity to the brush and having a lint-receiving opening 75 therein adjacent to the periphery of the brush, and a plate projecting through the said opening into the hollow member and serving as a chute for conducting the lint from the brush into the hollow member, and 80 preventing escape of the lint from the latter through the said opening.
15. In a cotton gin, the combination with supporting legs, of ginning mechanism including a brush cylinder having means co-operating therewith for forming a thin film of air adjacent thereto for driving the lint cotton therefrom, and a longitudinal conduit extending through the body of the gin and uniting the legs and arranged to receive the lint from the ginning mechanism, the said longitudinal conduit forming an 85 end exit for the lint.
16. The combination of a plurality of cotton gins arranged as a battery, each gin 90 having a conduit inclosed within the body thereof and opening out endwise through the same, the conduit provided with an opening and serving to receive and conduct the lint cotton out through the end of the gin, the conduits of the several gins being connected, and ginning mechanism in each 95 gin including a brush cylinder disposed adjacent to the opening of its corresponding conduit, the brush cylinders operating to 100 drive the lint cotton into and through the connected conduits.
17. A cotton gin having ginning and brush cylinders therein and also containing 105 within the body thereof a main lint receiving conduit having an inlet opening extending along the brush cylinder, the conduit extending from end to end of the gin close to the brush cylinder and adapted to receive and conduct lint cotton from the 110 said brush cylinder out through the end of the gin, and a guiding means interposed between the brush cylinder and the opening in the conduit, said conveying means projecting upwardly from the conduit at an 115 angle of inclination in proximity to a portion of the brush cylinder.
18. A cotton gin having ginning mechanism including a brush cylinder and containing within its body a main hollow lint 120 receiving member with an opening extending longitudinally thereof in receiving position with relation to the brush cylinder and along and close to the latter, and an inclined conveying means extending from the 125 130

opening of the main hollow member upwardly in proximity to the brush cylinder, the brush cylinder operating to forcefully drive air currents and the lint cotton downwardly over the guiding means into the hollow member, the said hollow member serving to conduct the lint cotton out through the end of the gin by the air currents forcefully created therein through the 10 operation of the brush cylinder.

19. A cotton gin having a ginning saw cylinder and a brush cylinder coöperating with the saw cylinder, a main hollow lint receiving and discharging conduit inclosed 15 within the body of the gin and extending from end to end of the gin along and close to the brush cylinder and opening out through the opposite ends of the gin, a brush cylinder creating an air current of 20 high velocity for driving the lint cotton downwardly from the saw cylinder into the said hollow discharging means and causing the lint cotton to travel through the latter and out through the end of the gin, 25 and an inclined guiding means interposed between the brush cylinder and the said hollow lint receiving and discharging means and operating to direct the air current carrying the lint cotton and the movement of 30 the current and cotton through the said discharging means.

20. In a cotton gin, the combination with supporting legs, of ginning mechanism including a brush cylinder operating to generate air currents of high velocity, and a longitudinal hollow member extending through the body of the gin and uniting the legs, the said longitudinal member having communication with the interior of the gin and 35 receiving said air currents laden with lint and forming an end exit for the lint.

21. A cotton gin having ginning and brush cylinders and containing within the body thereof a main lint conveying conduit 45 having an inlet opening along and in longitudinal relation to the brush cylinder and in proximity to the latter, the conduit being disposed beneath the brush cylinder and serving to receive the lint cotton directly 50 from said cylinder and conduct the cotton outwardly through the open end of the gin, and an inclined nozzle between the brush cylinder and the conduit.

22. In a cotton gin, the combination with 55 a ginning cylinder, of a brush cylinder having means coöperating therewith in addition to the brush material thereof to form air currents, a main lint receiving conduit arranged within the body of the gin and 60 extending longitudinally along and in proximity to the under portion of the brush cylinder to receive downwardly driven air currents laden with lint cotton from the brush cylinder and also serving to conduct 65 the lint cotton outwardly through one end

of the gin, and downwardly extending inclined guiding means between the upper portion of the conduit and the lower portion of the brush cylinder.

23. The combination with a plurality of 70 cotton gins arranged end to end and each having a ginning cylinder and a brush cylinder therein, of a main lint cotton receiving conduit disposed within the bodies of all the gins and extending longitudinally 75 through the latter adjacent to the brush cylinders and beneath said cylinders, the conduit serving to receive and conduct the lint cotton along, through and away from the gins, the brush cylinders operating to produce air currents of high velocity which are driven with the cotton into the conduit and carried along through said conduit by the air current producing action of the brush cylinders, the air currents within the conduits being augmented by the brush cylinders of the successive gins toward the outlet of the conduit, and downwardly extending inclined guiding means between the brush cylinders and the top portions of the 80 conduits within the gins.

24. The combination with a plurality of 85 cotton gins having ginning cylinders and brush cylinders therein, of a main lint receiving conduit arranged within and extending longitudinally through the bodies of the gins beneath and along the brush cylinders, the conduit having an opening in each gin close to the brush cylinder of the latter and serving to receive and provide a means 90 common to all the gins for discharging the lint from the latter, and downwardly extending inclined guiding means between the brush cylinders and the openings in the conduit for assisting in directing the air currents as to their entrance into the conduit 95 at such an angle as to create conveying currents within the conduit.

25. In a cotton gin, the combination with 100 ginning mechanism including a brush cylinder, of a conduit extending longitudinally through the gin and having an upper opening, the brush cylinder being disposed over the opening in the conduit and in close operative relation to the latter, and a chute extending at an angle into the conduit and having a lint plate forming a part thereof and extending above the conduit.

26. In a gin, the combination of ginning 105 mechanism, a roll box, upper and lower 120 grate rails, and a curved plate forming the back-hollow for the roll box, the lower portion of the curved plate embracing and forming an armor for the upper grate rail.

27. In a gin, the combination of ginning 125 mechanism including a roll box, upper and lower grate rails, a curved plate forming the back hollow for the roll box, the lower portion of this curved plate embracing and forming an armor for the upper grate rail, 130

and strengthening devices inserted through the upper rail and its armor.

28. A cotton gin having ginning mechanism including a brush cylinder, and a main hollow member contained within the body of the gin close to and along the brush cylinder to directly receive lint cotton and air currents from the said cylinder, an inclined guiding means being interposed between the member and the brush cylinder in tangential relation to both of the latter, the brush cylinder creating and driving the air currents laden with lint cotton into the hollow member and forcing the cotton outwardly through the said member.

29. A battery of cotton gins having ginning mechanism including brush cylinders, a hollow member extending through the bodies of the battery of gins and having inlets in proximity to the brush cylinders, the hollow member serving to receive the main lint cotton and forming a lint cotton outlet common to all the gins, and nozzles coöperating with each brush cylinder and the hollow member to cause the said cylinder by its operation to generate air currents of high velocity and drive said currents laden with lint cotton into the hollow member, the air currents forced into the hollow member by the brush cylinders being the sole means for moving the lint cotton through and outwardly from the said hollow member.

30. In a gin, ginning mechanism includ-

ing a brush cylinder, a hollow member inclosed within the body of the gin and forming an outlet for the lint cotton endwise through the gin and provided with a lint receiving opening adjacent to the brush cylinder, and means projecting into the member for preventing the return of the lint cotton through the lint receiving opening to the brush cylinder.

31. In a gin, ginning devices including a brush cylinder which creates air currents in the direction of its rotation, a hollow member inclosed within the body of the gin and forming an outlet for the lint cotton endwise through the gin and provided with a lint receiving opening adjacent to the brush cylinder, the brush cylinder and the air currents created thereby forcing and carrying the lint cotton from the ginning devices into and also creating lint laden air currents in the member, and means extending into the hollow member for preventing the lint laden air currents in the member from returning to and affecting the air currents created by the brush cylinder adjacent to the latter.

In testimony whereof I have hereunto set my hand in presence of two subscribing witnesses.
